Primary Examiner — Richelle G Shelton(74) *Attorney, Agent, or Firm* — Kirton McConkie; Brian Tucker(57) **CLAIM**

The ornamental design for a display screen with animated goal progress graphical user interface, as shown and described.

DESCRIPTION

FIG. 1 is the first image in a sequence for a display screen with animated goal progress graphical user interface showing my new design;

FIG. 2 is a second image thereof;

FIG. 3 is a third image thereof; and,

FIG. 4 is a fourth image thereof.

The appearance of the display screen with animated goal progress graphical user interface sequentially transitions between the images shown in FIGS. 1-4. The process or period in which one image transitions to another forms no part of the claimed design. The broken line showing the remainder of the graphical user interface is for environmental purposes only and forms no part of the claimed design.
